RAIL FASTENING

Jacob Rush Snyder, Cleveland, Ohio

Application March 3, 1943, Serial No. 477,792

10 Claims. (Cl. 238—349)

This invention relates to fastenings for railway rails and the like and more particularly to improved rail fastenings of the kind embodying a resilient clamp.

An object of the invention is to provide an improved rail clamp of the resilient type which can be economically manufactured and readily applied to railway rails and which is so constructed that it can be used with different forms of tie plates.

Another object of the invention is to provide an improved rail fastening of the character mentioned and in which the resilient clamp has rail-engaging lugs so formed and disposed that they are subjected to compression and afford maximum strength with minimum deflection.

A further object of the invention is to provide an improved rail fastening of the character mentioned and in which the resilient clamp has a spike-engaging portion adapted to engage the spike at a point close to the surface of the tie plate so as to obtain the maximum resistance of the spike to shear and bending.

Other objects and advantages of the invention will be apparent from the following description when taken in conjunction with the accompanying sheet of drawings, in which

Fig. 1 is a partial plan view showing a rail fastening embodying my invention;

Fig. 2 is a partial transverse sectional view taken through the same rail fastening as indicated by line 2—2 of Fig. 1;

Fig. 3 is a similar partial transverse sectional view taken through the clamp and tie plate to illustrate the approximate extent of deflection of the clamp;

Fig. 4 is a partial plan view of the clamp further illustrating the shape of the spike-engaging lug;

Fig. 5 is a partial plan view similar to Fig. 1 but showing another rail fastening embodying my invention; and

Fig. 6 is a partial transverse sectional view taken through such modified form of fastening as indicated by the line 6—6 of Fig. 5.

In the rail fastening illustrated in Figs. 1 and 2 I show a conventional railway rail 10 having a base flange 11 resting on a tie plate 12 which is in turn supported by a wood tie 13. The rail is held against the tie plate by means of a clamp 14 and a headed fastening member or spike 15 which extends into the tie through an opening 14a of the clamp and an opening 12a of the tie plate.

The tie plate 12 may be of conventional form comprising a substantially flat metal plate having

an upstanding transverse rib 16 providing a shoulder or abutment face 17 adapted to be engaged by a longitudinal edge of the rail flange 11. In addition to the opening 12a, the tie plate may also have a pair of spaced openings 18 which extend through or interrupt the rib 16 at correspondingly spaced points, as shown in Fig. 1. The openings 18 are provided in the tie plate 12 to accommodate conventional cut spikes in those cases where it is desirable to use cut spikes instead of my resilient clamp 14 in forming a rail fastening. The openings 12a and 18 may be of any appropriate size and shape, and in this instance the opening 12a is shown as being round and the openings 18 as being substantially square. As shown in Figs. 1 and 2, the opening 12a is located outwardly of the openings 18 and substantially midway therebetween, and the location of the openings 18 is such that the inner edge of each opening lies just inwardly of the upright plane containing the abutment face or shoulder 17.

The fastening member 15 may be a spike, as mentioned above, and in this instance is shown as being a screw spike having a helically threaded portion 15a and a head 15. The upper portion of the head may be of square or other polygonal shape to facilitate turning of the spike, and the lower face 19 of the head forms a surface or shoulder for engaging the clamp 14. The stem portion 15c connecting the head 15b and the threaded stem portion 15a may be a plain or unthreaded cylindrical portion which extends freely through the opening 12a of the tie plate and the opening 14a of the clamp.

The clamp 14 is of a novel construction and cooperates in a novel manner with the tie plate, rail and spike, as will be more apparent from the following detailed description. The clamp comprises a resilient plate member of a single thickness or ply which may be stamped or otherwise formed from sheet metal or plate stock and which may be suitably hardened or tempered. The clamp is generally flat, as compared with rail clamps of the type having a reversely bent or

angularly extending portion, but is preferably of a wavy or corrugated shape as shown in the drawing. One of the corrugations of the clamp forms an upwardly bowed intermediate section 20 through which the spike 15 extends and which is engaged by the head of the spike. At its outer end the clamp is provided with a substantially flat bearing portion 21 which rests on the tie plate 12. As can be seen from the drawing the tie plate 12 is of a conventional form and the portion thereof which extends around the open-

ing 12a and outwardly thereof and is engaged by the bearing portion 21 of the clamp is a substantially flat plain portion. The inner end 22 of the clamp is of relatively reduced width and has a rounded or convex bearing portion 22a which bears on the sloping face of the rail flange 11. A second corrugation or upwardly bowed section 23 of the clamp is located just outwardly of the end portion 22 and bridges over the upstanding rib 16 of the tie plate.

As shown in the drawing, the clamp 14 is constructed so as to have a pair of spaced integral lugs or sections 24 which are located on the rail side of the spike opening 14a and which extend in a direction away from such opening, that is to say, extend inwardly toward the rail 10. The lugs 24 may be formed by partially shearing corresponding portions of the clamp lying on opposite sides of the reduced end portion 22 and depressing or flattening such sheared portions so that the lugs will be substantially flat and will extend substantially parallel with the surface of the tie plate 12 in the completed rail fastening. The lugs 24 are spaced or located to correspond with the openings 18 of the tie plate 12 and are of a width and length such that they extend into and across the interruptions formed in the rib 16 by the openings 18 and their inner ends engage the vertical side face or edge 25 of the rail flange 11. The lugs 24 effectively prevent turning of the clamp about the spike 15 and when used with a tie plate which does not have the upstanding shoulder as shown in Figs. 5 and 6, they also provide means for gauging the rail and holding the same from shifting toward the spike. Since the lugs 24 are substantially flat and extend substantially parallel with the surface of the tie plate, it will be seen that these lugs are in compression or are adapted to be subjected to direct compressive forces as distinguished from bending or shearing forces. Under these circumstances, the lugs have maximum strength and rigidity and are not likely to be bent or sheared.

For transferring the outward thrust of the clamp 14 to the spike 15, I provide the clamp with a downwardly deflected or depending lug 26 which extends outwardly toward the opening 14a and whose free outer end engages the plain portion 15c of the spike. The lug 26 may be formed by partially shearing a section of the clamp lying substantially opposite the opening 14a and deflecting such sheared portion so that the lug formed thereby extends downwardly and outwardly and so that the outer end of the lug extends parallel with or approaches the plane of the upper surface of the tie plate. The free end of the lug may be recessed as indicated at 27 in Fig. 4 so as to conform to the shape of the spike and partially surround the same. With the lug 26 formed and located as just described, it will engage the spike at a point close to the upper surface of the tie plate 12 and it will be seen that by reason of the outward thrust of the clamp being applied to the spike at this point, the spike will have maximum resistance to shear and bending.

In addition to serving as a means for transmitting the thrust of the clamp to the spike 15, the lug 26 also forms a yieldable stop or indicator for limiting the deflection of the clamp and the extent to which the spike is to be driven into the tie. Fig. 3 shows the clamp 14 in broken lines in its free or released condition at which time the lug 26 is some distance above the surface

of the tie plate. When the spike is driven into the tie the later portion of its movement causes the clamp to be sprung or deflected from its broken line position to the full line position, at which time the lug 26 engages the surface of the tie plate and offers additional resistance to further inward movement of the spike. This additional resistance informs the section hand that the spike has been fully driven.

In Figs. 5 and 6 I show a rail fastening similar to that of Figs. 1 and 2 but using a tie plate 30 of a different form than the tie plate 12 above described. The tie plate 30 is identical with the plate 12 except that it does not have the upstanding rib 16 extending longitudinally along the base flange 31 of the rail 32. The clamp 33 and the spike 34 are identical with the clamp 14 and spike 15 described above and the ends of the clamp have bearing engagement on the rail flange and tie plate in the same manner as described above. The pair of spaced lugs 35 and the spike-engaging lug 36 are identical with the corresponding lugs 24 and 26 of the clamp 14. The lugs 36 extend substantially parallel to the tie plate in overlying relation to the openings 37 and their inner ends engage the edge of the rail flange 31. These lugs form a gauging means or shoulder which serves to hold the rail against shifting toward the spike 34.

Although I have shown my rail clamp being used with two different forms of tie plates, it will be understood, of course, that Figs. 2 and 6 may represent opposite ends of the same tie plate, in which case one edge of the rail flange is gauged or located by the rib 16 and the opposite edge is gauged or located by the lugs 35 of the clamp 33.

From the foregoing description and the accompanying drawing it will now be readily understood that I have provided an improved rail fastening of the kind embodying a resilient clamp and it will also be seen that the clamp is of a novel form and can be economically manufactured and quickly applied to railway rails. Additionally, it will be seen that my improved rail fastening is adaptable to different forms of tie plates which is an important factor in reducing the number of parts required to be carried in stock.

While I have illustrated and described my improved rail fastenings in a more or less detailed manner, it will be understood, of course, that I do not wish to be limited to the particular details and arrangements herein disclosed but regard my invention as including all changes and modifications coming within the scope of the appended claims and which do not constitute a departure from the spirit of the invention.

Having thus described my invention, I claim:

1. A clamp for use in a rail fastening, comprising a single-thickness corrugated resilient metal plate having an upwardly bowed intermediate portion provided with an opening for a fastening member, said opening being located substantially on the central transverse axis of the plate, said plate having a portion adapted to extend over and engage a flange of the rail and a partially sheared portion forming an integral lug which extends laterally toward said opening for engagement with said fastening member and is located a substantial distance below the top of said upwardly bowed intermediate portion, said plate also having a pair of partially sheared portions located on the rail side of said opening but extending in a direction away from the opening and forming a pair of substantially

flat integral lugs contiguous to the sides of said plate and adapted to engage the edge of the rail flange.

2. A clamp for use in a rail fastening, comprising a single-thickness corrugated resilient metal plate having an upwardly bowed intermediate portion provided with an opening for a fastening member, said opening being located substantially on the central transverse axis of the plate, said plate having a portion adapted to extend over and engage a flange of the rail and a partially sheared portion forming an integral lug which extends laterally toward said opening for engagement with said fastening member and is located a substantial distance below the top of said upwardly bowed intermediate portion, the end of said lug being recessed to conform substantially with said fastening member, said plate also having a pair of partially sheared portions located on the rail side of said opening but extending in a direction away from the opening and forming a pair of substantially flat integral lugs contiguous to the sides of the plate and which terminate short of the end of the plate and are adapted to engage the edge of the rail flange.

3. In a rail fastening, a tie plate adapted to receive a flanged rail thereon and having an opening spaced outwardly from the edge of the rail flange and a substantially flat plain portion extending around and outwardly of said opening, a clamp comprising a resilient metal plate having end portions bearing respectively on said rail flange and on said substantially flat plain portion of said tie plate and also having in an intermediate portion thereof an opening located substantially on the central transverse axis of the clamp and overlying the opening of the tie plate, and a fastening member extending through the openings of the clamp and tie plate for holding said clamp in flexed condition, said clamp having a depending portion on the rail side of the fastening member which extends downwardly and outwardly and engages the fastening member at a point below the body of said clamp and adjacent said flat plain portion of said tie plate, the clamp also having a pair of spaced lugs located contiguous to the sides of the clamp and on the rail side of the fastening member and which extend inwardly relative to the fastening member and engage the edge of the rail flange.

4. In a rail fastening, a tie, a tie plate adapted to receive a flanged rail thereon and having an opening spaced outwardly from the edge of the rail flange, a clamp comprising a single-thickness corrugated resilient metal plate having end portions bearing respectively on said rail flange and tie plate and also having an upwardly bowed intermediate portion provided with an opening overlying the opening of the tie plate, and a headed fastening spike extending into the tie through the openings of the clamp and tie plate and holding the clamp in flexed condition for clamping the rail against the tie plate, said clamp having a partially sheared portion forming an integral lug located on the rail side of the spike and extending outwardly into engagement with the spike at a point adjacent the surface of the tie plate, the clamp also having a pair of partially sheared portions located on the rail side of the spike and contiguous to the sides of the clamp and forming substantially flat lugs which terminate short of the inner end of the clamp and whose ends engage the edge of the rail flange.

5. A rail fastening as defined in claim 3 in which the end of said depending portion of the clamp is recessed to partially surround the fastening member.

6. In a rail fastening, a tie plate adapted to receive a flanged rail thereon and having an upwardly bowed intermediate portion provided with an opening spaced outwardly from said portion and a pair of openings interrupting said portion at spaced points, a clamp comprising a single-thickness resilient metal plate having end portions bearing respectively on the rail flange and tie plate and having an upwardly bowed intermediate portion provided with an opening located substantially on the central transverse axis of the clamp and overlying the first-mentioned opening of the tie plate, a headed fastening member extending through the clamp and tie plate for holding the clamp in flexed condition, said clamp having spaced portions contiguous to the sides thereof and forming substantially flat lugs extending away from the fastening member and across the interrupted portions of said portion into engagement with the edge of the rail flange, the clamp also having a deflected portion located substantially opposite the fastening member and on the rail side thereof forming an outwardly extending lug whose free end engages the fastening member adjacent the surface of the tie plate.

7. In a fastening for a rail having a base flange provided with a substantially vertical longitudinal side edge, a rail support adapted to receive said base flange thereon and having a substantially flat plain portion spaced from said side edge, said support having an opening therein at a point between said side edge and said plain portion, a clamp comprising a resilient metal plate having an upwardly bowed intermediate portion provided with an opening which overlies the opening of said support and is located substantially on the central transverse axis of the clamp, said clamp also having inner and outer ends of which the inner end has a portion overlying and bearing upon said rail flange and the outer end bears on said substantially flat plain portion of said support, a headed fastening member engaging said upwardly bowed portion and extending through the openings of said support and clamp and causing the latter to clampingly hold said rail against said support, said inner end of the clamp having relatively depressed substantially flat portions on opposite sides of said overlying portion and which engage said side edge of the rail flange so as to receive the lateral thrust of the rail in direct compression.

8. In a fastening for a rail having a base flange provided with a substantially vertical longitudinal side edge, a rail support adapted to receive said base flange thereon and having a substantially flat plain portion spaced from said side edge, said support having an opening therein at a point between said side edge and said plain portion, a clamp comprising a resilient metal plate having an upwardly bowed intermediate portion provided with an opening which overlies the opening of said support and is located substantially on the central transverse axis of the clamp, said clamp also having inner and outer ends of which the inner end has a portion overlying and bearing upon said rail flange and the outer end bears on said substantially flat plain portion of said support, a headed fastening member engaging said upwardly bowed portion and

extending through the openings of said support and clamp and causing the latter to clampingly hold said rail against said support, said inner end of the clamp having relatively depressed substantially flat portions on opposite sides of said overlying portion and which engage said side edge of the rail flange so as to receive the lateral thrust of the rail in direct compression, said clamp also having a relatively depressed portion lying on the rail side of and substantially opposite the clamp opening, the last mentioned portion of the clamp engaging said fastening member at a point below said upwardly bowed portion.

9. In a fastening for a rail having a base flange provided with a substantially vertical longitudinal side edge, a rail support adapted to receive said base flange thereon and having an upstanding transverse rib located to be engaged by said edge of the rail flange, said support also having an opening therein outwardly of said rib and a pair of openings interrupting said rib at spaced points and a substantially flat plain portion extending around the first mentioned opening and outwardly thereof, a clamp comprising a resilient metal plate having an upwardly bowed intermediate portion provided with an opening which overlies said first mentioned opening and is located substantially on the central transverse axis of the clamp, said clamp also having inner and outer ends of which the inner end has a portion overlying and bearing upon said rail flange and the outer end is substantially flat and has coextensive bearing engagement with said substantially flat plain portion of said support, a headed fastening member engaging said upwardly bowed portion and extending through the first mentioned and overlying openings of said support and clamp and causing the latter to clampingly hold said rail against said support, said inner end of the clamp having relatively depressed substantially flat portions on opposite sides of said overlying portion and extending substantially parallel with the upper surface of said support and across the interrupted portions of said rib into engagement with the vertical side

edge of the rail flange so as to receive the lateral thrust of the rail in direct compression.

10. In a fastening for a rail having a base flange provided with a substantially vertical longitudinal side edge, a rail support adapted to receive said base flange thereon and having an upstanding transverse rib located to be engaged by said edge of the rail flange, said support also having an opening therein outwardly of said rib and a pair of openings interrupting said rib at spaced points and a substantially flat plain portion extending around the first mentioned opening and outwardly thereof, a clamp comprising a resilient metal plate having an upwardly bowed intermediate portion provided with an opening which overlies said first mentioned opening and is located substantially on the central transverse axis of the clamp, said clamp also having inner and outer ends of which the inner end has a portion overlying and bearing upon said rail flange and the outer end is substantially flat and has coextensive bearing engagement with said substantially flat plain portion of said support, a headed fastening member engaging said upwardly bowed portion and extending through the first mentioned and overlying openings of said support and clamp and causing the latter to clampingly hold said rail against said support, said inner end of the clamp having relatively depressed substantially flat portions on opposite sides of said overlying portion and extending substantially parallel with the upper surface of said support and across the interrupted portions of said rib into engagement with the vertical side edge of the rail flange so as to receive the lateral thrust of the rail in direct compression, said clamp also having a relatively depressed portion lying on the rail side of and substantially opposite said overlying opening of the clamp, the last mentioned portion of the clamp engaging said fastening member at a point below said upwardly bowed portion and adjacent the upper surface of said support.

JACOB RUSH SNYDER.
